TOE PROTECTOR

Isadore Kiwad, Westwood, N. J.

Application February 27, 1951, Serial No. 212,926

3 Claims. (Cl. 128—153)

1

This invention relates to protector devices for the toes of the feet and has for its primary object the provision of a highly improved and greatly simplified form of construction and arrangement for toe protectors of the type shown and described in my U. S. Patent No. 2,581,851, dated November 28, 1950, for Toe Protector.

A further object of my invention is to provide a toe protector of the character described which shall be so simple in design as to be relatively inexpensive to manufacture whereby the user thereof could easily afford to discard and replace the same after a relatively short period of wear.

Another object of my invention is to provide a toe protector of the character described which shall be characterized by the ease with which it can be worn and removed and which shall at the same time be effective to a high degree for the purposes intended.

Other objects of my invention will become apparent from the description of the invention to follow, or will hereinafter be more fully pointed out.

In the accompanying drawings,

Fig. 1 is a top plan view of a toe protector constructed and arranged according to my invention;

Fig. 2 is a cross-sectional view taken substantially along the line 2—2 of Fig. 1;

Fig. 3 is a perspective view of the protector shown in Figs. 1 and 2, but of smaller size and illustrating the manner of folding and bending of the parts thereof, ready for use;

Figs. 4 and 5 are schematic illustrations as viewed from the bottom of the foot of the user and illustrating the manner of placing the toe protectors in proper position;

Fig. 6 is a perspective view similar to Fig. 3 but showing the same in effective position on one of the toes when viewed from the top of the foot;

Fig. 7 is a plan view similar to Fig. 1, but illustrating a modified form of my invention; and

Figs. 8 and 9 are views similar to Figs. 3 and 5 respectively, but illustrating the Fig. 7 form of invention.

Referring now in detail to the drawings, I have illustrated in Figs. 1 through 6 a toe protector, constructed and arranged in accordance with my invention and comprising a single sheet 20 of soft, resilient material of the nature of cotton, wool, nylon, rayon or silk, preferably felted and of suitable length, width and thickness to satisfactorily form the functions intended. Beginning at points 21, spaced inwardly a predetermined distance x from the transverse edge 20a of the sheet 20, I provide a pair of longitudinal slits 22 and 23 running in a direction toward the transverse edge 20b of the sheet 20. It is noted that the slits 22 and 23 extend for a distance substantially equal to one-half the distance between the points 21 and the edge 20b of the sheet 20. The purpose and function of the distance re-

2

lationships just described will soon become apparent. I then interconnect the slits 21 and 22 with a transverse slit 24 thus forming a tongue portion 25, bendable to a plane at an angle to the plane of the sheet 20.

It is thus seen from the above description that I have produced by a simple operation which may be performed in a single stamping with a suitable die, a toe protector which may readily be applied to the foot in the following manner:

As best seen in Fig. 3, the tongue portion 25 is pressed forwardly to the dotted line position 25¹, leaving an opening 28 in the material of the sheet 20. The portion 26 adjacent the opening 28 is then folded inwardly to the dotted line position 26¹ which is substantially parallel to the bent tongue 25¹. The angularly folded toe protector as just described is then mounted on a selected toe, in this case, the toe A shown in Fig. 4, with the said toe A projecting through the opening 28 until the lowermost portion of the spaces between the toes is reached, or to any other depth desired, such as, for example, that shown in Fig. 5. It is noted that by placing the toe protector 20 on the toe A, the bent tongue 25¹ thereof will be protectively interposed between the big toe T and the toe A, while the part 26¹ will be protectively interposed between the toes A and B. If another toe protector unit 20 is placed on the toe C, the spaces between the toes B and C and C and D will be protected.

It is thus seen that a toe protector 20 may be selectively placed on any toe depending upon the needs of the wearer and that two toe protectors are all that are required for maximum protection between all the toes of one foot.

The material of the sheet 20 being soft and flexible, the toe protector of my invention will readily adjust itself to the foot without discomfort to the wearer.

In view of the fact that the length Y of the tongue 25 is substantially equal to the length Z of the portion 26, the said tongue and portions when bent as shown in Figs. 3 and 6 will be substantially of equal size.

In Figs. 7, 8 and 9 I have illustrated a modified form of my invention in which instead of a single tongue member cut from the sheet of material I provide a plurality of such tongues which form openings spaced along the length thereof so that the toe protector may be mounted on more than one toe in which tongue and sheet portions may be protectively interposed between all the toes of one foot at one operation.

As noted in Fig. 7, I provide a longitudinal sheet 30 of suitable toe protecting material having upper and lower longitudinal marginal edges 30a and 30b and transverse marginal edges 30c and 30d. In the manner described in connection with the Figs. 1 through 6 form of my invention, I provide upper and lower slits 31 and 32 starting

from a point spaced x -distance from the edge 30c and extending for a predetermined distance Y toward the edge 30d. A transverse slit 33 interconnects the slits 31 and 32 to thereby provide a first tongue member 35 which when bent angularly away from the plane of the sheet 30 to the position 35¹ (see Fig. 8) leaves an opening 36 designed to receive a toe therethrough. Spaced x -distance from the transverse slit 33 a second set of upper and lower slits 40 and 41 are provided, which are in substantial alignment with the slits 31 and 32 and which are interconnected by a transverse slit 43 forming a second tongue 45 bent out from a second opening 46 adapted to receive the next adjacent toe therethrough. Similarly, at a distance X from the transverse slit 43 I provide a pair of longitudinal slits 51 and 52 and an interconnecting transverse slit 53, forming a third tongue 55 bent out from the opening 56 which in turn receives the next adjacent toe therethrough. According to my invention the portion 58 of the sheet 30 between the transverse slit 53 and the transverse edge 30d is substantially equal to the longitudinal dimension Y of the tongues 35, 45 and 55 so that when the said portion 58 is angularly bent to the position 58¹ (Fig. 8) it will serve as another tongue to be interposed between adjacent toes.

It is thus seen from the above description that when the toe protector shown in Figs. 7 and 8 is mounted on the toes of the foot as illustrated in Fig. 9 in which the foot is viewed from the bottom, in one operation the spaces between all the toes are protected. Thus, as noted in Fig. 9, the tongue 35 is interposed between the big toe T and the toe A; the tongue 45 is interposed between the toes A and B; the tongue 55 is interposed between the toes B and C; and the end portion 58 is interposed between the toes C and D.

As best seen in Fig. 7, the transverse slits 33, 43 and 53 may each be made wider than their longitudinal slits to facilitate the mounting of the toe protector on the toes.

As noted in Figs. 7, 8 and 9, the portion U between the upper slits 31, 40 and 51 and the longitudinal edge 30a is of less width than the portion L between the lower slits 32, 41 and 52 and the lower longitudinal edge, the wider bottom portion L being designed to fit underneath the toes in the hollow parts thereof.

I claim:

1. As an article of manufacture, a toe protector of the character described comprising longitudinal sheet of flexible material, a plurality of integral tongue portions in the plane of said longitudinal sheet, and of a given length, said tongue portions being spaced from each other a given distance along the length of said sheet, said sheet being provided at one end thereof with an imperforate portion substantially equal in length to the length of a single tongue portion, each of said tongue portions being bendable away from the plane of said sheet to form corresponding openings in the plane of said sheet, said openings being adapted to receive therethrough a toe of the foot of a user with each of said tongue and said imperforate portion being thereby positioned between a pair of adjacent toes.

2. As an article of manufacture, a toe protector of the character described comprising a sheet of flexible material having first and second longitudinal edges and first and second transverse edges, a first longitudinal through slit in said sheet, starting at a point adjacent said first transverse edge, and extending in a direction toward said second transverse edge; said first longitudi-

nal slit being disposed on one side of the longitudinal axis of said sheet and terminating at a point spaced from said second transverse edge, a distance substantially equal to the length of said first longitudinal slit, a second longitudinal through slit, starting at a point adjacent said first transverse edge and extending in a direction toward said second transverse edge, said second longitudinal slit being disposed on the opposite side of the longitudinal axis of said sheet, from that of said first longitudinal slit, and of a length substantially equal to the length of said first longitudinal slit, a transverse through slit interconnecting and communicating with said first and second slits, whereby a tongue member is provided which is bendable away from the normal plane of said sheet leaving a toe receiving opening; whereby upon the insertion of a toe into said toe receiving opening, said tongue member may be protectively disposed between the toe in said opening and the next adjacent toe, and the portion of said sheet between said first slit and said second transverse edge may be protectively disposed between the toe in said opening and the next adjacent toe opposite said first mentioned adjacent toe.

3. As an article of manufacture, a toe protector of the character described comprising a sheet of flexible material having first and second longitudinal edges and first and second transverse edges, a first longitudinal through slit in said sheet, starting at a point adjacent said first transverse edge, and extending in a direction toward said second transverse edge; said first longitudinal slit being disposed on one side of the longitudinal axis of said sheet and terminating at a point spaced from said second transverse edge, a distance substantially equal to the length of said first longitudinal slit, a second longitudinal through slit, starting at a point adjacent said first transverse edge and extending in a direction toward said second transverse edge, said second longitudinal slit being disposed on the opposite side of the longitudinal axis of said sheet, from that of said first longitudinal slit, and of a length substantially equal to the length of said first longitudinal slit, a transverse through slit interconnecting and communicating with said first and second slits, whereby a tongue member is provided which is bendable away from the normal plane of said sheet leaving a toe receiving opening; whereby upon the insertion of a toe into said toe receiving opening, said tongue member may be protectively disposed between the toe in said opening and the next adjacent toe, and the portion of said sheet between said first slit and said second transverse edge may be protectively disposed between the toe in said opening and the next adjacent toe opposite said first mentioned adjacent toe; said transverse slit being wider than said first and second longitudinal slits.
